Patented June 4, 1918.

UNITED STATES PATENT OFFICE.

ALBERT WANNER, JR., OF NEW YORK, N. Y.

UMBRELLA AND SIMILAR STAND.

1,268,190.

Specification of Letters Patent.

Patented June 4, 1918.

Original application filed June 17, 1916, Serial No. 104,149. Divided and this application filed April 5, 1917. Serial No. 159,859.

To all whom it may concern:

Be it known that I, ALBERT WANNER, Jr., a citizen of the United States, residing at New York city, in the county of New York and State of New York, have invented certain new and useful Improvements in Umbrella and Similar Stands, of which the following is a specification.

This invention relates to stands, racks and the like of the class including a pedestal and a horizontally arranged supporting structure carried by the pedestal, and it consists in certain improvements in stands of this class whereby a structure strong and durable, attractive in appearance, capable of being readily assembled and disassembled, and adapted to be manufactured at the minimum of cost is produced. My invention is herein illustrated as an umbrella stand or rack, but it is to be understood that it may be applied to other constructions including a pedestal or columnar upright and a horizontal supporting structure adapted to be fitted over the pedestal or upright, the feature of fitting the supporting structure over the pedestal or upright in such a manner as to obtain a substantial and rigid bearing on the latter being one of the essential characteristics of the invention.

30 In the accompanying drawing,

Figure 1 is a side elevation of the improved stand or rack;

Fig. 2 is a plan view of the supporting structure thereof;

35 Fig. 3 is a side elevation of said structure; and,

Figs. 4 and 5 are sectional views on lines y—y of Fig. 2.

40 a is the pedestal or columnar upright, the same being slightly tapered upwardly. To form a base for this upright there are provided the radial legs b which may be attached thereto in any suitable manner but which are preferably removably jointed thereto as in my application for patent bearing the Serial No. 103,049, filed June 12th, 1916, in conformity with one object of the invention, which is that the rack or stand may be of the knock-down class, if desired, and capable of being packed in the smallest possible compass for storing and shipping. As in my said application, the upright a may be extended upwardly as indicated by broken lines in Fig. 1 and carry at the top a

cluster of hooks, thus to form a clothes tree.

c is the horizontal supporting structure, fitted over the upright a and made to have a substantial and rigid support thereon, to these ends being constructed as follows, referring particularly to Figs. 2 to 5.

The said structure in plan is shown in the drawing as circular. It includes a plate formed of laminated sheets d of fibrous material (preferably wood having its grain crossed) cemented together, and the radial brackets e.

The plate has a central hole f adapted to fit the upright a and it includes an integral peripheral portion g and radial portions h together forming openings i which are adapted to receive the umbrellas, canes and the like.

The brackets e may each be formed of a single piece of wood arranged vertically and having a horizontal top face and an inner upright face j, the latter being inclined to the same angle as each side face of the upright a due to the upward taper of the latter and flush with the margin of the hole f.

45 Each bracket e may be secured to the under side of the plate c by brads k as shown in Fig. 4, such bracket underlying a radial portion h of the plate, or each bracket may have a dove-tailed tongue-and-groove connection with the under side of a radial portion h of the plate as shown at l in Fig. 5, the tongue and groove being extended preferably into several layers d of the plate. To make the joint thus formed permanent, so that this form of the supporting structure may be uniform in character glue m may be employed in the joint.

50 A supporting structure thus formed is adapted to be fitted over the upright a in the manner shown in Fig. 1, being jammed down thereon so that the taper of the upright will insure a tight joint being produced. In the actual construction shown, the supporting structure binds against the tapering upright both in the plane of the segmental plates and below the same, where the downwardly projecting portions of the brackets e have contact with the upright.

55 This application constitutes a division of my application Serial No. 104,149, filed June 17th, 1916.

Having thus fully described my inven-

tion, what I claim as new and desire to secure by Letters Patent is:—

1. In combination, a columnar upright and a horizontal supporting structure fitted over the upright and including a horizontal support proper formed of horizontal layers of sheet-material cemented together, said support proper including a peripheral continuous marginal portion and radial portions together forming openings for the article to be received.

2. In combination, a columnar upright and a horizontal supporting structure fitted over the upright and including a horizontal support proper and radial brackets each bearing inwardly against the upright, said support proper including a peripheral con-

tinuous marginal portion and radial portions together forming openings for the articles to be received and each bracket being secured to one such radial portion.

3. In combination, a columnar upright and a horizontal supporting structure fitted over the upright and including a horizontal support proper and radial brackets each bearing inwardly against the upright, said support proper including a peripheral continuous marginal portion and radial portions together forming openings for the articles to be received and each bracket having a dove-tail-joint connection with one such radial portion.

In testimony whereof I affix my signature.

ALBERT WANNER, JR.
